(57) **CLAIM**

The ornamental design for a ladder, as shown and described.

DESCRIPTION

FIG. 1 is a perspective view of a ladder showing an embodiment of the design;

FIG. 2 is a front view of the ladder shown in FIG. 1;

FIG. 3 is a rear view of the ladder shown in FIG. 1;

FIG. 4 is a left side view of the ladder shown in FIG. 1;

FIG. 5 is a right side view of the ladder shown in FIG. 1; and,

FIG. 6 is a top view of the ladder shown in FIG. 1.

The uneven broken line representations in the drawings are for illustrative purposes only and form no part of the claimed design.
